UNITED STATES PATENT OFFICE.

THOMAS W. MILLER, OF ASHLAND, OHIO, ASSIGNOR TO THE FAULTLESS RUBBER COMPANY, OF ASHLAND, OHIO, A CORPORATION OF OHIO.

CLOSURE FOR INFLATABLE BODIES.

1,098,286.

Specification of Letters Patent. Patented May 26, 1914.

Application filed March 9, 1914. Serial No. 823,450.

To all whom it may concern:

Be it known that I, THOMAS W. MILLER, a citizen of the United States, residing at Ashland, in the county of Ashland and State 5 of Ohio, have invented certain new and useful Improvements in Closures for Inflatable Bodies, of which the following is a specification.

My invention relates to toy balloons and 10 similar inflatable articles, and has for its object to provide the article with an improved means for retaining thereon the inflating medium, which readily may be manipulated either to close or to open the same.

15 In the accompanying drawing:—Figure 1 is a side elevation of a toy balloon in collapsed or uninflated condition and embodying my improved device, the operating collar thereon being shown in section. Fig. 2 is a similar view, showing the balloon inflated and the parts adjusted to retain the inflating medium therein. Fig. 3 is a detail sectional view of the balloon neck and the apertured mouth-piece inserted therein.

25 Fig. 4 is a view similar to Fig. 3 showing a slightly modified construction. Fig. 5 is a detail perspective view of the operating collar.

Similar numerals of reference denote 30 corresponding parts in the several views.

In the said drawing the reference numeral 1 denotes the inflatable body of the balloon or similar article, and 2 the neck thereof, which is open and preferably has 35 formed integrally thereon an enlarged flange 3. Inserted in said neck 2 is a mouth-piece or plug 4, the same being formed of a solid piece of any suitable material, such as wood, hard rubber, metal or the like, and 40 being of a diameter sufficiently large to present a substantially flat inner surface 5 materially larger than the normal diameter of the neck 2. Said mouth-piece or plug is centrally apertured at 6 and has its periphery grooved at 7 to receive the flange 3 of the neck 2, as shown. Disposed on the neck 2 is a collar 8, somewhat elongated, and 45 formed of any suitable material, such as metal, semi-vulcanized rubber or the like, 50 it being necessary only that it have a certain rigidity against longitudinal yield.

In assembling the collar 8 is first slipped onto the neck 2 of the article while the latter is in a collapsed state, and the mouth-piece or plug 4 is inserted into the neck 2

of the article until the flange 3 is disposed in the groove 7 therein, where it will be retained against displacement by the stretched condition of said neck, in a manner similar to the application of a rubber nipple to the 60 neck of a nursing bottle. The article now may be inflated by forcing air or other fluid through the mouth-piece or plug, either by the application of the lips thereto or by means of any suitable mechanical fluid supply device, and, when inflated, by twisting either the mouth-piece or plug 4 with respect to the body 1, or said body with respect to said mouth-piece or plug, the neck 2 will be caused to assume a twisted condition, shown in Fig. 2, which effectually will 65 prevent the escape of the fluid from the body 1. Upon now releasing the parts, it will be found that the collar 8 will be forced by the expanded body 1 into contact with 70 that portion of the neck 2 lying against the larger inner face 5 of the mouth-piece or plug 4, and will by friction automatically retain said body 1 and mouth-piece or plug 4 against any rotation relative to each other, 75 and thus will retain said neck 2 in its twisted condition, whereby egress of the inflating fluid effectually will be prevented. To 80 deflate the article it is necessary only to untwist the neck 2, which may be done by manipulating the mouth-piece or plug 4 with respect to the body 1, which will open said neck 2 for the escape of the inflating fluid through the aperture 6.

In Fig. 4 I have shown a slightly modified construction, the neck 2 being additionally retained in position on the mouth-piece or plug 4 by winding a thread 9 thereon just back of the flange 3 and in the groove 7.

90 While I have described my invention as applicable particularly to toy rubber balloons, still I contemplate its use in connection with any inflatable articles, such as foot ball bladders, striking ball bladders, 95 and the like, it being capable of use with any article inflated through a flexible neck.

Having thus described my invention, what I claim as new and desire to secure by Letters Patent, is:—

105 1. The combination with an inflatable body, of means for automatically retaining a portion of the same in a twisted condition to prevent passage of the inflating medium therethrough.

2. The combination with an inflatable body, and an open flexible inflating neck thereon, of means for automatically retaining said neck in a twisted condition to prevent passage of the inflating medium therethrough.
3. The combination with an inflatable body, and an open flexible inflating neck thereon, of means operated through the pressure exerted by said body when inflated for automatically retaining said neck in a twisted condition to prevent passage of the inflating medium therethrough.
4. The combination with an inflatable body, an open flexible inflating neck thereon, and an apertured plug fitted into said neck, of a collar loosely disposed on said neck and of a smaller diameter than that of said plug, said collar operating when said body is inflated and said neck is twisted to retain said neck against untwisting through its frictional contact between said inflated body and said plug.
5. An article of the character described, embracing an inflatable body, a flexible open neck therefor, an apertured plug fitted onto said neck, and a collar of smaller diameter than that of said plug loosely disposed on said neck between said body and said plug in position to be forced against said plug by the pressure of said body when inflated.
6. An article of the character described, embracing an inflatable body, a flexible open neck therefor, an apertured plug of larger diameter than said neck and having a peripheral groove to receive and retain the outer end of said neck when the latter is stretched thereon, and a collar of smaller diameter than that of said plug loosely disposed on said neck between said body and said plug in position to be forced against said plug by the pressure of said body when inflated.
- In testimony whereof I have hereunto set my hand in the presence of two subscribing witnesses.

THOMAS W. MILLER.
